UNITED STATES PATENT OFFICE.

GEORGE BEN PERKINS, OF WEINGARTEN, MISSOURI.

PLIERS.

Application filed August 16, 1926. Serial No. 129,432.

The invention relates to combination pliers and has for its object to provide a device of this character having cooperating right-angled jaws movable in parallel planes, and which jaws may be used for gripping an article at the end of the pliers or to one side thereof, said side gripping being preferably used for tightening and removing nuts.

10 A further object is to provide the rear side of the upper jaw with a rearwardly extending bifurcated member adapted to be used as a tack or nail puller and with a vertically disposed and rearwardly extending cutter 15 blade cooperating with a cutter blade on the upper side of the handle member and adapted to be used for cutting wire or other material.

20 A further object is to provide the upper movable jaw with a downwardly extending integral shaft slidably mounted in the head of one of the handle members and provided with an opening in its rear side into which a curved arm of the pivoted handle member 25 extends, and by means of which pivoted handle member the shank may be controlled in its movement in either direction.

20 A further object is to provide the lower end of the shank with an axially disposed 30 punch, which may be used for setting nails or for punching purposes, by placing the same on the nail head and hammering on the movable jaw.

35 With the above and other objects in view the invention resides in the combination and arrangement of parts as hereinafter set forth, shown in the drawing, described and claimed, it being understood that changes in the precise embodiment of the invention may be 40 made within the scope of what is claimed without departing from the spirit of the invention.

In the drawings:—

45 Fig. 1 is a perspective view of the pliers, Fig. 2 is a rear perspective view of the head of the pliers, and

Fig. 3 is a vertical longitudinal sectional view through the head of the pliers.

50 Referring to the drawing, the numerals 1 and 2 designate adjacent handle members and 3 the enlarged head carried by the handle member 1. Slidably mounted in bearings 4 of the head 3 is a vertically disposed shank 5, the rear side of which is provided 55 with an inwardly and upwardly inclined

recess 6, into which the finger 7 of the handle member 2 extends. Handle member 2 is pivotally mounted within a recess 8 in the under side of the head 3 and on a pivot pin 9. It will be seen that when the handle 60 members 1 and 2 are forced together, the shank 5 will be moved downwardly and the gripping jaw 10 carried by the upper end thereof will be forced downwardly to a position where it will cooperate with the 65 fixed jaw 11 of the head 3. Extending outwardly from one side of the jaw 10 at a right angle and in the same plane therewith is a jaw 12 which cooperates with a jaw 13 which extends outwardly from the 70 side of the head 3 and at a right angle to the jaw 11; therefore it will be seen that cooperating jaws are provided at one side of the pliers as well as at the end thereof, and said side jaws 12 and 13 may be used for 75 gripping a nut thereby allowing the pliers to be used as a wrench and the handle members 1 and 2 to be spaced outwardly from the nut that is being turned, and at the same time disposing the jaws where the 80 relatively strong leverage can be obtained.

Extending rearwardly from the rear side of the jaw 10 is a bifurcated member 14, which is spaced from the upper side of the head 3 and is provided with a V-shaped recess 15 adapted to receive therein a nail or 85 tack head when the device is used for pulling a tack or nail, and at which time the device is in reverse position and the upper side of the jaw 10 is used as a fulcrum. Extending rearwardly from the rear side of the jaw 10 and formed integral with the member 14 is a downwardly extending cutter blade 16, which cutter blade cooperates with the cutter blade 17 formed integral with the 90 upper side of the head 3, and which cutter blades cooperate for cutting material, such for instance as wire. It will be noted that the members 14 and 16 are positioned where they will not interfere with the use of the 95 device for other purposes, and the member 16 is braced by the member 14. Therefore it will be seen that the cutter blade 16 will not break. The lower end of the shank 5 is provided with a punch 18, which may be 100 used for punching holes or setting nails as desired, at which time the operator can impart percussive blows on the upper end of the shank. Handle member 1 is preferably 105 provided with a flattened portion 19, and the 110

handle member 2 with a sharpened end 20, which end portions may be used for various purposes.

From the above it will be seen that a combination tool is provided which is simple in construction and compact, and is provided in a single combination with means whereby the functions of many tools may be attained, thereby providing a tool which 10 is particularly adapted for general work of several kinds and one which is particularly desirable for automobilists where storage space is limited.

The invention having been set forth what 15 is claimed as new and useful is:—

A tool comprising a handle member, a chambered head carried by said handle mem-

ber, a stationary jaw carried by the outer end of said head, a movable jaw above said head and cooperating with the stationary 20 jaw, right-angularly disposed cooperating jaws carried by the head and the movable jaw and at a right angle to the handle member, a shank carried by the movable jaw, said shank being slidably mounted in the 25 head and having a recess in the rear side thereof, a handle member pivotally mounted in the chamber of the head, and a finger carried by said last-named handle member and extending into the recess in the rear 30 side of the shank.

In testimony whereof I hereunto affix my signature.

GEORGE BEN PERKINS.
